UNITED STATES PATENT OFFICE.

JENNINGS GRANT AMBROSE, OF HOUSTON, TEXAS.

HEADING-HOLDER ATTACHMENT FOR TYPE-WRITERS.

SPECIFICATION forming part of Letters Patent No. 739,277, dated September 22, 1903.

Application filed June 13, 1903. Serial No. 161,335. (No model.)

To all whom it may concern:

Be it known that I, JENNINGS GRANT AMBROSE, a citizen of the United States, residing at Houston, in the county of Harris and State 5 of Texas, have invented a new and useful Improvement in Heading-Holder Attachments for Type-Writers, of which the following is a specification.

My invention relates to attachments for 10 type-writing machines, and is especially directed to an attachment for use in the preparation of bills or the like to facilitate the work of tabulating, and has for its objects to produce a device of this character which will be 15 simple of construction, efficient in operation, one which will carry a plurality of headings and may be readily operated to bring any one of the headings into action, and one in which the attachment may be readily removed and 20 applied, thus permitting the rapid interchanging from one holder to another in changing from one class of work to another.

To these ends the invention comprises the 25 novel details of construction and combination 30 of parts more fully hereinafter described.

In the accompanying drawings, Figure 1 is a 35 front elevation of the carriage of a type-writing machine having my improved attachment applied thereto. Fig. 2 is a perspective view of the attachment removed and showing the parts disassembled. Fig. 3 is a detail section on the line 3-3 of Fig. 1. Fig. 4 is a cross-section through the body of the attachment. Fig. 5 is a view in elevation of the headings 40 removed from the holder.

Referring to the drawings, 1 indicates the carriage of a type-writing machine which has applied to its front rail the usual scale 2, secured in place by means of screws. These 45 parts may be of the usual construction, as they constitute no part of my invention.

My invention consists in a holder 3, which is removably secured to the machine in a manner presently described and constitutes, in effect, a supplemental scale for facilitating accurate spacing in tabular work. This holder is preferably of triangular form and is composed of three metal plates 4 of a length equal to the length of the usual type-writer scale 50 and each having its longitudinal edges bent inward to form longitudinal flanges 5. The plates are assembled by soldering or other-

wise uniting them at the points of contact throughout their length when brought back to back in triangular disposition. By this arrangement the device presents three faces, to each of which is applied a scale or indicator consisting of a printed heading cut from the bill or like form which is being used in the machine and inserting said strip into the holder with its edges engaged beneath the longitudinal flanges 5, the three strips or headings employed in the present instance being represented in Fig. 5.

The holder 3 is rotatable for bringing any 65 one of its sides into active position to present the heading carried thereby to the view of the operator. In order to permit the ready rotation of the holder, I provide the same at opposite ends with pintles 6, 7, which are journaled, respectively, in bearings carried by arms or clips 8, 9. The arms or clips are secured to the carriage of the machine by the screws which attach thereto the usual scale, the only difference in the parts residing in 75 the fact that in the present instance I employ for the attachment of clip 9 a thumb-screw, which permits of the clip being readily removed by hand for the purpose which will presently appear. The clip 8 has associated 80 therewith in any suitable manner, but preferably by soldering or brazing, a leaf-spring 10, which extends through a slot 11 in the bearing of pintle 6 and bears upon the latter, which has its surface at this point provided 85 with angular faces upon which the spring presses, thus holding the holder against accidental rotation, but at the same time permitting of its being rotated by hand to bring any 90 one of its faces to view, as above explained.

In order to permit ready removal of the holder 3 for interchanging from one holder to another, I form the holder at its ends with longitudinally-disposed sockets of triangular or other polygonal form in cross-section, in 95 which are seated the inner ends of the pintles, which are of course of similar form in cross-section and which are held frictionally in the sockets and are readily removable therefrom, the pintle 7 being comparatively short to permit of its more ready removal from its socket. By this arrangement when it is desired to change from one holder to another the thumb-screw is removed, releasing clip 9, thus per-

mitting the pintle 7 being withdrawn from the holder. The holder is then removed from the other pintle and a second holder placed in position upon the pintles, as will be readily understood.

Attention is here directed to the fact that the clips 8 9 have their upper portions just above the point of attachment with the carriage bent outward at an angle, thus obviating interference of the holder with the platen and enabling the operator to more readily grasp the holder for rotating the same.

From the foregoing it will be seen that I produce a device which is very simple of construction, one which may be readily applied to the machine, and one which in practice will efficiently perform its functions and materially facilitate the tabulation of bills or the like, and in attaining these ends I do not limit myself to the precise details herein shown, inasmuch as minor changes in the form, proportion, and manner of assemblage of the parts may be made without departing from the spirit of my invention.

Having thus described my invention, what I claim is—

1. A device of the class described compris-

ing a rotatable holder carrying a plurality of headings, pintles associated with the holder, attaching-clips in which the pintles are journaled, one of said clips being slotted and the adjacent pintle provided with angular faces, and a spring associated with the slotted clip, extending through the slot therein and engaging the angular faces on the pintle.

2. A device of the class described comprising a rotatable holder carrying a plurality of headings, and provided with longitudinally-disposed sockets of polygonal form in cross-section, pintles of similar form in cross-section removably mounted in the sockets and provided beyond the ends of the holder with cylindrical portions, attaching-clips having bearings receiving the cylindrical portions of the pintles, and means for removably attaching the clips to a type-writer.

In testimony that I claim the foregoing as my own I have hereto affixed my signature in the presence of two witnesses.

JENNINGS GRANT AMBROSE.
